UNITED STATES PATENT OFFICE.

ARNOLD THOMPSON AND HERBERT J. S. DENNISON, OF TORONTO, ONTARIO, CANADA.

HAND-GRENADE.

1,327,451.

Specification of Letters Patent.

Patented Jan. 6, 1920.

Application filed March 11, 1918. Serial No. 221,631.

To all whom it may concern:

Be it known that we, ARNOLD THOMPSON and HERBERT J. S. DENNISON, both subjects of the King of Great Britain, and residents 5 of the city of Toronto, county of York, Province of Ontario, in the Dominion of Canada, have invented certain new and useful Improvements in Hand-Grenades, as described in the following specification and 10 illustrated in the accompanying drawings, that form part of the same.

The principal objects of this invention are, to devise a grenade which may be handled with safety and may be thrown 15 with great accuracy for considerable distances.

A further and important object is to obviate the dangers due to the uncertainties of time fuses and to devise a grenade which 20 though it will not explode with ordinary handling will be extremely dependable in its explosion upon impact when thrown.

A still further object is to devise a structure which is extremely simple to manufacture, safe to handle in assembling and 25 may be made at very low cost.

The principal feature of the invention consists in the novel construction and arrangement of parts, whereby the detonation 30 of the explosive charge is effected by the pivotal action of a weighted member adapted to be swung on its pivot through the impact of the grenade alighting.

In the accompanying drawings, Figure 1 35 is a top plan view of the improved grenade.

Fig. 2 is a top plan view of the grenade with the cover removed and showing the parts set in the position for detonating.

Fig. 3 is a top plan view with the cover 40 removed showing one of the striker members for detonating in the released position.

Fig. 4 is a cross sectional view through the line *a—b* of Fig. 2.

Fig. 5 is a cross sectional view through 45 the line *c—d* of Fig. 3, showing the arrangement of the detonator and striker.

Fig. 6 is an elevational view of the inner face of the pivotal operating member.

Numerous forms of bombs and hand 50 grenades have been brought into use, some being detonated by time fuses and others by impact. The time fuse has several elements of uncertainty resulting in danger which it is very desirable to avoid. The 55 greatest difficulty experienced in regard to impact detonating bombs has been to make

them sufficiently sensitive to explode with certainty upon being thrown and yet to avoid the possibility of accidental premature explosion in the hands of the thrower or 60 through careless handling. The present invention has been devised to overcome these difficulties and to simplify the construction.

The invention is herein shown as applied to a grenade of the disk form, the casing being formed of the top and bottom sections 1 and 2 which are flanged at the edges and threaded together forming a double convexed disk. 70

A pin 3 is secured centrally in one of the disk sections and the outer end fits snugly into a receiving orifice in the other section. The inner surface of each of the disks is formed with a slightly raised boss 4 sur- 75 rounding the base of the pin.

A sheet metal holder 5 of segmental form, preferably slightly less than half a circle is formed to the contour of the interior cavity in the casing and the upper and lower plates 80 are provided with lugs 6 which rotatably encircle the pin 3 and are supported between the bosses 4 so that the holder swings freely upon its pivot clear of the walls of the casing. The inner face 7 of the holder 85 is provided with holes 8 therein for the purpose which will hereinafter appear.

The holder 5 is loaded with suitable shrapnel 9 preferably of disk form as illustrated in Fig. 4 having sharp cutting edges. The 90 circumferential edge of the holder 5 is flattened at 10 and a lug projection 11 is formed at the juncture of each of the flattened portions and the inner face 7.

A sheet metal casing 12 for containing 95 the explosive is formed to the contour of the interior of the outer casing and is a segment of less than half a circle. This explosive container fits snugly into the outer casing and is held in a fixed position, the central 100 portion being shaped to clear the lugs 6 of the holder 5. The casing 12 is provided with openings 13 in the inner face 14 in which are secured suitable ferrules 15 for holding the detonators. 105

The openings 13 are arranged equidistant from the center and centrally of the depth of the face 14.

Striker members 16 are pivotally supported upon the pivot pins 17 which are secured in 110 the lower member 2 of the casing close to the outer flange and arranged close to the

face 14 of the explosive casing 12. These striker members are preferably formed of sheet metal having laterally bent lugs 18 journaled upon the pins 17 and conical 5 striker pins 19 are secured to or formed upon the said striker members and so arranged as to strike centrally upon the detonators arranged in the openings 13. The striker members extend outwardly from the 10 pins 19 in a shape preferably concentric to the inner wall of the flange of the casing 2 and engage the lugs 11 of the pivotal holder 5 in sliding contact and the extreme outer ends 20 are preferably bent slightly inward 15 to form a resisting element to engage the said lugs.

The striker members are actuated to swing upon their pivots by coil springs 21 encircling the pivot pins and the outer 20 curved portions 22 are thus held in spring engagement with the lugs 11. This spring contact holds the holder 5 from swinging upon its pivot unless the grenade is moved with a quick movement and suddenly 25 checked as considerable impact is required to force the lugs 11 past the inwardly turned ends 20 of the striker. When the holder 5 is swung upon its pivot with such force as to clear the striker the spring behind same 30 swings it upon its pivot and brings the striker pin down upon the center of the detonator. Numerous tests have shown that after releasing one of the strikers the weighted holder rebounds and releases the other so 35 that there is a double factor in the certainty of operation in the event of either detonator failing.

In actual practice the projecting lugs 11 and inturned ends 20 of the strikers are so 40 formed that the force of impact which might be caused by careless handling or by a bomb thrower accidentally striking his hand against a wall or against a comrade, or even allowing the bomb to drop would not 45 be sufficient to clear these points but the greater impact of the weight of the bomb carried through a few feet further space is sufficient to cause the weighted holder to swing upon its pivot to clear either one of 50 the strikers and explode the charge.

It will be readily understood from this description and drawing that the heavily loaded pivotal member will swing with considerable force upon its pivot when the 55 movement of the mass is suddenly arrested and while this swinging movement may be utilized to act directly upon the detonator the action might not be sufficiently positive for safety.

60 It is found by actual test that the striker members and the engaging lugs upon the shrapnel holder 5 can be so made that a grenade can be dropped for a distance of three or four feet, more or less without the 65 strikers being released but if it is thrown for

a distance of a few feet exceeding that for which it is set it will release the strikers on every occasion. Such a grenade will be extremely safe in the hands of a thrower and will be as equally deadly at its objective. 70

The weighted holder is secured in a central position by a safety pin 23 which is inserted through the outer casing and holder and is provided with a withdrawing ring 24.

The uncertainty in the use of time fuse 75 grenades has been a very serious matter and many instances have occurred in the present war where time bombs have been returned after having been thrown, with deadly effect upon the original thrower. This difficulty 80 is entirely overcome with an impact grenade and the present structure obviates the many difficulties found in the use of this class of weapon.

An additional element of safety may be 85 utilized in the use of a delay detonator which will allow a slight delay between the detonation of the cap and that of the portion which detonates the main charge.

The principle of operation is herein shown 90 and described as applied to a small hand grenade but it must be understood that it may be applied to any size of bomb and may be utilized in other shapes of bombs with equal facility.

The structure herein shown is extremely 95 simple and the factor of safety is very high, both as regards handling when loaded and in assembling. The strikers are first assembled into the casing and the loaded shrapnel holder is then placed upon the pivot pin and the strikers set. The safety pin is then inserted through the hole 25 in the outer casing and extends into and through the holder. The explosive container 12 is then placed in 100 position and the upper half of the casing is screwed into place and when finally secured the safety pin is passed through the registering hole 26 in the upper section of the outer casing and the outer ends turned over, thus 105 securing the shrapnel holder from any possibility of movement and making it absolutely impossible for the strikers to be released no matter what kind of usage the bomb is subjected to.

A further and important feature of this 110 invention is that there are no plugs, screws, levers, caps or any operating parts which can be tampered with to cause accidents and and it does not require any manipulation or 115 special manner of throwing and as it is thus perfectly balanced it may be thrown with very great accuracy and for much greater distances than other forms of grenades at present in use.

120 What we claim as our invention is:—

1. In a grenade, a weighted member pivotally supported to rotate in a fixed plane, an explosive container, and means arranged 125 in the plane of rotation for holding said 130

member stationary and for effecting the detonation of said explosive through the rotation of said weighted member.

2. In a grenade, a weighted member pivotally supported to rotate in a fixed plane, an explosive container, and detonating means engaging said weighted member on either side and restraining it from rotation and adapted to be released upon the swinging of said member through the impact of the grenade.

3. A grenade, comprising an outer casing containing an explosive chamber having detonators arranged each side of the center, a weighted member pivotally supported centrally of said casing and adapted to swing upon its pivot through the force of impact, and spring actuated striker members arranged each side of the casing and adapted to explode said detonators, said striker members being held against their actuating springs by said pivotal member and released upon the swinging thereof.

4. A grenade, comprising, a casing, an explosive container having detonators, a holder pivotally supported within the casing and carrying a load of shrapnel and adapted to swing upon its pivot and to effect the detonation of the explosive through the swinging force caused by the impact of the grenade.

5. A grenade, comprising an outer casing,

an explosive chamber contained within said casing and having detonators arranged therein adjacent to the sides, spring actuated striking members pivotally secured within the casing and adapted to swing on their pivots and to strike the detonators and having extension ends formed with inturned extremities, a weighted segmental member pivotally mounted within the casing and having its periphery engaging the extension ends of said striker members and formed with projections adapted to engage the inwardly turned ends of said strikers and cooperating therewith to obstruct the release of the strikers through the swinging of the loaded holder.

6. A grenade, comprising an outer casing formed of a pair of conical shaped members secured together at their edges, a pivot pin arranged upon the axis of said casing, an explosive containing casing of segmental form arranged within the casing and held in a fixed position, suitable detonators arranged in the inward face of said segmental casing, a weighted segmental member pivotally supported on said pivot pin and axially rotatable thereon, and means actuated by said pivotal member for detonating the charge.

ARNOLD THOMPSON.
HERBERT J. S. DENNISON.
